UNITED STATES PATENT OFFICE.

LIPA POLINKOWSKY, OF ANTWERP, BELGIUM, ASSIGNOR TO WESTERN ELECTRIC COMPANY, INCORPORATED, OF NEW YORK, N. Y., A CORPORATION OF NEW YORK.

TELEPHONE SYSTEM.

Application filed January 5, 1923. Serial No. 610,752.

To all whom it may concern:

Be it known that I, LIPA POLINKOWSKY, a citizen of Russia, residing at Antwerp, Belgium, have invented certain new and useful Improvements in Telephone Systems, of which the following is a full, clear, concise, and exact description.

This invention relates to telephone exchange systems and particularly to automatic telephone systems such as are employed for small private branch exchanges.

Heretofore such systems have either employed switches having movement in two directions or switches rotatable in one direction only over a bank of contacts. In those systems in which the switches have movement in two directions such switches are of a complicated construction and consequently expensive and liable to get out of order easily, while in those switches in which the brushes have movement in one direction only, the brushes must be moved in response to a large number of operations of the dial switch of the calling subscriber to enable a reasonable number of lines to be accessible to the switch.

It is the principal object of the present invention to provide an improved system of this character in which the apparatus employed may be of very simple construction and which may be operated under the control of an impulse transmitting device in a simple manner to establish a connection to one of a number of lines.

In accordance with this invention a telephone system comprises a selecting switch operable to extend a connection to one of a plurality of lines accessible thereto, said switch being operable for a digit of the designation of the desired line under the control of the calling party and then to be moved automatically and independently of the calling party until a predetermined position is reached depending upon the digit first called, the switch being movable from this position in response to the remainder of the designation of the desired line to extend the connection thereto. Further, the switch may comprise a plurality of sets of brushes

engaging different sets of contacts, the particular set of brushes to be taken into use during the call being determined by the digit first called.

In accordance with a further feature of this invention a plurality of switching devices are arranged to be associated with the calling line, the particular switch taken into use during the call being determined by the digit first called, as is also the position from which this switch shall be moved for the remainder of the designation of the desired line.

In carrying this invention into effect the selecting switch preferably takes the form of a final selector switch adapted to extend connections directly to called subscribers' lines and comprises a plurality of sets of line and test brushes adapted to be moved over a corresponding number of sets of contacts, by the operation of a stepping magnet. This magnet is adapted to receive impulses under the control of the usual line relay which is in turn controlled by the usual dial switch of the calling subscriber. Certain of the contacts engaged by the switch brushes are connected to certain controlling relays of the switch, so that upon the switch being operated for a particular tens digit representing the first digit of the designation of the desired line, certain of these controlling relays are energized.

After the switch has been moved in response to the impulses transmitted for the first digit, a circuit is closed for the stepping magnet independent of the control of the line relay, which circuit passes in series through contacts controlled by the magnet itself. This circuit is closed by the operation of the controlling relays and causes the magnet to operate automatically to step the brushes quickly from the position to which they are set by the impulses representing the first digit. A sensitive relay is provided, the circuit of which is controlled by the controlling relays and which extends over certain contacts in the switch bank, so that the relay is energized quickly immediately a particular one of these contacts is reached

and this relay, upon energizing, opens the circuit of the stepping magnet so that the switch is brought to rest immediately in engagement with this contact. In the preferred embodiment of the switch the bank consists of twenty two contacts arranged in a circle or arc and the stepping contacts upon which the sensitive relay may be energized are preferably the first contacts of the switch constituting the first normal position and the middle or eleventh contacts constituting the second normal position. The switch is moved from these contacts in response to the impulses representing the units 15 digit.

In the preferred form of the invention the connecting circuit terminates in two or more final selector switches which are arranged in parallel each having its own stepping magnet and sets of brushes. A particular switch is operated in response to the impulses for the first digit and determines the energization of certain controlling relays which in turn determine the switch 20 which shall be subsequently used in the extension of the call and also the position from which said switch shall be moved for the remainder of the designation of the desired line.

30 The dialing and busy tones are preferably generated by a single apparatus consisting of a set of relays which operate in succession to open and close a circuit through a winding of a tone coil to generate a tone in the secondary winding thereof.

35 Ringing current is also generated by an apparatus consisting of a set of relays and a stepping magnet operating to step a brush over a set of contacts arranged in a circle to cause an intermittent pulsating electromotive force to be generated in the secondary winding of the ringing transformer.

The accompanying drawing formed by placing Fig. 2 to the right of Fig. 1, illustrates one form of the invention in which the connecting circuit terminates in a pair of final selector switches. Fig. 3 shows a modified form of subscriber's circuit, used in connection with a group of equivalent lines.

50 The invention is of such a nature that it will be more fully understood by a description of the operation of the system. Upon the subscriber at substation T_1 removing his receiver, the line relay 10 energizes in a circuit from battery, left-hand winding of relay 10, 11^a, through the calling party's station and back through 11^c, right-hand winding of relay 10 to earth. The relay 10, upon energizing, closes at its contact c a circuit

60 for the relay 35 from battery, 35, 10^c, earth. Relay 10 also closes at its contact a a circuit connecting the cut-off relay 11 to the test terminal of the calling line. Connected across the left-hand winding of the cut-off relay 11 is a non-inductive resistance which

is provided for the purpose of enabling the test relay 16 of the line finder switch LF to operate quickly in series with the cut-off relay. Relay 35, upon energizing, closes the circuits of the stepping magnets 36 of the line finder switches similar to the line finder switch LF of the connecting circuit shown in the drawing. This circuit may be traced from battery, 36, 36^a, 35^a, 34^b, 16^b, to earth. The stepping magnets thereupon operate to rotate the brushes a , b , c and d of the line finder switches with which they are associated over the contacts in their banks in search of the terminals of the calling line, the stepping magnets automatically opening their own energizing circuits at their contacts a at each energization. The brushes of all free line finder switches having access to the group of subscribers' lines, of which the calling line is one, therefore hunt for the calling line and when the terminals of the calling line are found the test relay energizes in a circuit which may be traced from battery, left-hand winding of the cut-off relay 11, 11^a, 10^a, test terminal and brush c , 39^a, 34^m, 90 winding of test relay 16, 35^c, resistance 1 to earth. The test relay 16 together with the cutoff relay 11, operate in this circuit. The test relay 16 opens at its contact b the circuit before traced for the stepping magnet 36 so that the brushes of the line finder switch LF are brought to rest in engagement with the contacts of the desired line. Upon the closure of the contact a of the test relay 16 the resistance 1 is short-circuited and upon the closure of the contact a of the cutoff relay 11, a locking circuit is provided for these two relays from battery, both windings of cutoff relay 11, 11^a, test terminal and brush c , 39^a, 34^m, 16, 16^a, earth. The test relay is of low resistance and the short-circuiting of the resistance 1

100 at its contact a causes the potential upon the test terminal to be such as to maintain the calling line busy against all other seeking line finder switches. The cutoff relay 11 upon energizing opens at its contacts d and f the circuit before traced for the line relay 10 so that this relay now deenergizes and opens at its contact c the circuit for the relay 35. This relay deenergizes and opens at its contacts a the circuits of the stepping magnets 36 of all the other hunting line finder switches. The line relay 10 also opens at its contact a the circuit of the cut-off relay 11, but the latter relay has locked up as before described at its contact a over a circuit including the test relay 16 so that relay 11 is maintained energized.

110 The relay 13 is normally short-circuited at the contact b of the test relay 16 so that as soon as the test relay 16 energizes and opens its contact b , relay 13 energizes over a circuit in series with the winding of the stepping magnet 36 from battery, 36, 36^a, 35^a, 120 130

34^b, 13, earth, the winding of relay 13 being of sufficient resistance to prevent the stepping magnet energizing in series therewith. Relay 13 closes at its contact *a* a locking circuit for itself independently of the relay 34 and at its contacts *g* and *l* connects the stepping relay 14 to the calling line so that battery is supplied to the line through the two windings to the stepping relay in series. The relay 14 energizes in series with the calling line and at its contact *a* closes a circuit for the slow acting relay 15 from battery, 15, 14^a, earth. Relay 13 at its contact *c* also closes a circuit for the relays 17 and 19 from battery, 13^c, left-hand winding of relay, 19, 34^c, normal terminal engaged by brush *g* of the first final selector switch FSI, 30^b, normal terminal engaged by brush *g*² of the second final selector switch FSII, 28^f, 25^f, 17, earth. Relay 17, upon energizing, closes at its contact *c* a circuit connecting the test relay 16 to the test terminal independently of the relay 34, this circuit being traceable from brush *c* of LF, 39^a, 17^c, 16, 16^a, earth. At its contact *a* relay 17 prepares the circuit for the stepping magnet 37 of the first final selector switch FSI which circuit extends from battery, 37, 31^d, 24, 17^a, 14^a, 13^c, 23^a, to earth, this circuit being opened at this time at contact *d* of the relay 14 and contact *a* of the relay 23.

The relay 19, upon energizing, closes a locking circuit for itself at its contact *e* through the relay 50 of the tone apparatus TA shown at the lower left-hand corner of the drawing. This circuit may be traced from battery, 50, right-hand winding of 19, 19^c, 26^d, 15^c, to earth. The relay 50, upon energizing, closes a circuit at its contact *a* for the relay 51 of the tone circuit from battery, 51, 51^b, contact *a* of key 52, 50^a, earth. A circuit is also closed from battery through the primary winding of the tone coil 53, contact *b* of key 52, 51^b, contact *a* of key 52, 50^a, to earth. The relay 51 energizes in the circuit previously traced and opens at its contact *b* its own energizing circuit and the circuit before traced extending from the primary winding of the tone coil 53. Upon opening its contact *b* the relay 51 deenergizes and will consequently again close its contact *b*. In this manner the current flowing through the primary winding of the tone coil 53 is intermittently broken and consequently an alternating electromotive force is generated in the secondary winding of the tone coil. The energization of the relay 19 causes the closure of its contact *a* and *c* and this operation connects the secondary winding of the tone coil 53 to the calling line. The calling subscriber hears the tone in his receiver and is thereby informed that he may operate his dial switch in accordance with the first digit of the called number.

The circuit traced through the relay 50 and contact *e* of relay 19 maintains this relay energized. At its contact *g* relay 19 closes a circuit for the relay 34 which extends from battery, 19^c, resistance 60, 34, 17, 70 earth. The relays 34 and 19 are arranged to energize slowly so as to insure that the relay 17 will close its front contacts before relay 34 opens its back contacts.

Upon the relay 34 energizing it closes a locking circuit for itself at its contact *e*, this circuit being traceable from battery, 34^c, resistance 60, 34, 17, to earth. The relay 34 by closing its contact *g* prepares a short circuit to earth for the relay 17 which may be traced from one side of relay 17, contact *g* of 34, 15^d, to earth. This short circuit is, however, maintained open at the contact *d* of the relay 15 which is maintained energized at contact *a* of the stepping relay 14 as long as the receiver of the calling party is off this hook. The relay 34 by opening its contact *f* opens the circuit of the left-hand operating winding of the relay 19 and by closing its contact *e*, closes a circuit for the relay 23 from battery, 23, 34^c, normal contact engaged by brush *g* of the final selector switch FSI, 30^b, normal contact engaged by brush *b*² of second final selector switch FSII, 28^f, 25^f, 17, earth. The relay 23 upon energizing, closes at its contact *a* the impulse circuit extending through the stepping magnet 37 of the first final selector switch FSI from battery, 37, 31^d, 24, 17^a, 14^d, 13^c, 23^a, earth, this circuit being maintained open at the contact *d* of the stepping relay 14.

Upon the calling party hearing the dialing tone transmitted from the secondary winding to the tone coil 53 he operates his dial switch for the first digit of the called subscriber's number. The first series of impulses always operates the stepping magnet 37 of the first final selector switch FSI so that the brushes of that switch are moved a number of steps in accordance with the number of impulses of the first digit of the called subscriber's number into engagement with corresponding contacts in the bank of the switch. The position to which the brushes of this switch is set in accordance with the first digit determines the closure of particular circuits determining the subsequent operation of the switch in a manner which will be hereinafter more fully described.

Upon the calling subscriber releasing his dial switch the circuit of the stepping relay 14 is broken a number of times in accordance with the digit dialed and the circuit of the stepping magnet is closed from battery, 37, 31^d, 24, 17^a, 14^d, 13^c, 23^a, to earth, this circuit being closed at the contact *d* of the relay 14 at each deenergization of the relay. At each impulse the relay 14 opens its

contact *a* but the relay 15 is constructed so as to retract its armature slowly so that it remains energized during the whole period of the transmission of the impulses. The 5 stepping magnet 37 of the first final selector switch FSI operates in accordance with the impulses transmitted thereto over the circuit before traced to step the brushes *e*, *f*, *g*, *e*₁, *f*₁, *g*₁, over the contacts in the bank of 10 the switch and into engagement with a particular set of contacts thereof in accordance with a number of impulses transmitted for the first digit of the called number. The relay 24 is constructed to operate quickly but 15 to release its armature slowly so that it energizes immediately upon the first closure of the impulse circuit upon the deenergization of the relay 14 and at its contact *a* closes a 20 circuit for the relay 26 from battery, 26, 24^a, earth.

Relay 26, upon energizing, closes at its contact *e* a circuit for the relay 25 from battery, right-hand winding of relay 25, 26^e, to earth. Relay 25, upon energizing opens 25 the connection from the calling line through the cord circuit to the brushes of the final selector switches FSI, FSII, and at its contact *f* it disconnects the test brushes *g* and *g*² from the winding of the relay 17. Relay 30 26 upon energizing maintains the stepping circuit independently of the contact *a* of the relay 23, this circuit now being traceable from battery, 37, 31^a, 24, 17^a, 14^a, 26^e, 15^e, to earth. At the end of the first series of 35 impulses the stepping relay 14 remains deenergized for a short period of time during which the calling party winds up his dial switch in accordance with the second digit of the called subscriber's number and the relay 40 24 thereupon becomes deenergized and opens at its contact *a* the circuit of the relay 26 and this relay in turn opens at its contact *e* the circuit before traced for the relay 25 so that relays 26 and 25 now deenergize.

With the particular arrangement described the calling subscriber may dial any one of the digits 2, 3, 4, 5, 6, 7, 8 and 9 as the first digit of the called party's line, the digits 0 and 1 being reserved for calls to 45 the attendant as hereinafter described. The operation of the switch and the various controlling relays energized in response to the dialing of the various first digits will now be described.

55 *6 dialed as tens digit.*

Upon the calling subscriber transmitting the digit 6 as the first or tens digit of the called subscriber's number, the stepping 60 magnet 37 of the first final selector switch FSI is operated in the manner before described to move the brushes of the switch six steps into engagement with the sixth set of contacts in its bank. When now at the 65 end of the series of impulses the relay 25 de-

energizes in the manner before described a circuit is completed from battery, through the left-hand winding of the relay 33, 18^t, 25^b, 28^d, brush *f*² engaging the normal contact of the final selector FSII, brush *f*, of 70 the first final selector switch FSI and the sixth contact in the row of contacts over which it moves and into engagement with which contact it has been moved by means of the tens series of impulses, right-hand 75 winding of relay 27, 26^b to earth. Relay 27 thereupon operates and closes at its contact *c* a locking circuit for itself from battery, 34^e, resistance 60, 27^e, both windings of relay 27, 26^b, to earth. At its contact *g* relay 80 27 also closes a circuit for the relay 18 from battery, 18, 20^d, 27^g, 15^e, to earth. The relay 18 thereupon energizes and closes a locking circuit for itself at its contact *g* independently of relay 27 from battery, 18, 20^d, 85 18^g, 15^e, earth.

Relay 18 also closes a circuit for the relay 40 of the ringing apparatus shown at the right-hand lower corner of Fig. 1 from battery, 40, 18^a, 25^d, 26^h, 23^b, to earth, but at 90 contact *a* of relay 27 an energizing circuit is closed for relay 25 from battery, right-hand winding of 25, 27^a, to earth, so that the relay 25 energizes and again opens the connection from the calling line to the brushes of the first and second final selector switches FSI and FSII in the manner before described and prevents the relay 40 from energizing. A circuit is also closed at contact *e* of relay 95 27 for the stepping magnet 37 of the final selector switch FSI from battery, 37, 31^a, 37^a, 38^a, 27^e, 25^e, 26^b, 23^b, to earth. This circuit includes contact 37^a which is controlled by the magnet 37 so that the stepping magnet now operates automatically in the circuit 100 described to step the brushes of the first final selector switch FSI automatically from the position to which they were set in response to the tens digit into engagement with the eleventh set of contacts in the bank, which 105 is the second normal set of contacts upon which the brushes may come to rest, the magnet interrupting its own circuit at each step taken by opening contact *a*. Upon the eleventh set of contacts in the bank of the first final selector switch being reached, a circuit is closed for the quick operating sensitive relay 23 from battery, 23, 32^f, eleventh contact engaged by brush *g* of FSI, 110 30^b, first normal contact and brush *g*² of the second final selector switch FSII in normal position, 28^t, 25^e, 26^t, 27^a, to earth. The relay 23 operates immediately the brushes of the final selector switch FSI reach the eleventh set of contacts and opens the circuit 115 before traced for the stepping magnet 37 of this switch at its contact *b*. The calling subscriber will cause the brushes of the final selector switch FSI to be moved from the eleventh or second normal contacts by the 120

125

115

120

125

130

transmission of the units impulses in the manner hereinafter to be fully described and as soon as the subscriber begins to transmit these impulses the relays 27 and 25 will 5 energize.

7 dialed as tens digit.

- Should the calling subscriber transmit the digit 7 as the tens digit these impulses will 10 actuate the stepping magnet 37 of the first final selector switch FSI in the manner before described and will cause the brushes of this switch to be moved into engagement with the seventh set of contacts in the bank. 15 In this position circuits are closed to cause the relays 27, 25 and 18 to be energized in a manner similar to that before described when the digit 6 was dialed and the stepping magnet 37 will be automatically actuated so as 20 to cause the brushes of the first final selector switch FSI to be moved from position 7 into engagement with the eleventh set of contacts in the bank. When the final selector switch FSI is set to position 7 a circuit is also closed 25 at the brush *e* for the relay 29 which may be traced from battery, right-hand winding of relay 29, contact 7, brush *e*, normal contact and brush *e*² of final selector switch FSII, 28^b, 25^b, 18^a, right-hand winding of 30 33 to earth. Relay 29 energizes and at its contact *c* closes a locking circuit for itself including the slow operating relay 28 from battery, 28, right-hand winding of 29, 29^c, 15^c to earth. The relay 29 is arranged to be 35 quick acting so that it will operate before relays 27 and 25 operate while the relay 28 being slow to operate insures that the relay 27 will energize and close a locking circuit for itself before the relay 28 opens its back 40 contacts. Relay 28, upon energizing, disconnects the brushes *e*², *f*² and *g*² of the second final selector switch FSII and the brushes *e*, *f* and *g* of the first final selector switch FSI at its contacts *h*, *d* and *f*, respectively, and at its contacts *a*, *c* and *e* connects 45 up the brushes *e*³, *f*³, *g*³ of FSII and *e*₁, *f*₁ and *g*₁ of the final selector switch FSI. As, however, the brushes of the second final selector switch FSII remain in engagement 50 with their normal contacts, the switch not being operated during this call, the brushes *e*₁, *f*₁ and *g*₁ are the brushes which are used in extending the connection to the line of the called party. It will, of course, be understood that all the brushes of the final selector switch FSI will be moved over their 55 associated contacts but as the brushes *e*, *f* and *g* are disconnected and the brushes *e*₁, *f*₁ and *g*₁ only connected to the talking circuit, the latter set of brushes are those which are used. In this particular instance the second final selector switch FSII remains inoperative with its brushes in engagement with their normal contacts throughout the call. 60 65 The stepping magnet 37 of the final selector

switch FSI operates to move the brushes from position 7, to which they are moved in response to the dialing of 7 as the tens digit, into engagement with the second normal or eleventh contacts in the bank and 70 when these contacts are reached a circuit is closed for the quick acting sensitive relay 23 from battery, 23, 32^f, eleventh contact in the bank engaged by brush *g*₁, normal contact and brush *g*₃ of FSII, 28^e, 25^e, 26^c, 27^a, 75 to earth. Relay 23 energizes immediately the brushes reach the eleventh or second normal contact and opens in the manner before described the circuit of the stepping magnet 37 so that the brushes are brought to rest in engagement with the eleventh set of contacts. The switch FSI is now in a position to be moved by the units impulses as will be hereinafter described. 80

8 dialed as the tens digit.

Should the calling party transmit 8 as the tens digit the brushes of the first final selector switch FSI will be moved 8 steps from normal into engagement with the eighth set 90 of contacts in the bank of the switch. In this position a circuit is closed as when the switch was operated for the digit 7 for the relay 29 and this relay closes at its contact *c* a locking circuit for itself including the slow operating relay 28 which also energizes. A circuit is also closed for the relay 32 which may be traced from battery, left-hand winding of 33, 18^r, 25^b, 28^a, *f*², and normal contact engaged thereby, *f* and the eighth contact engaged thereby, left-hand winding of 32, 26^b, earth. Relay 32 upon energizing closes a locking circuit from battery, 34^c, resistance 60, 32^a, both windings of relay 32, 26^b to earth. Relay 32 upon energizing 95 also closes a circuit for the relay 27 which may be traced from battery, 34^c, resistance 60, 32^a, both windings of relay 27, 26^b, to earth. Relay 32 opens at its contact *f* the circuit for the sensitive relay 23 which would 100 otherwise exist to the eleventh set of contacts in the bank of the switch. The stepping magnet 37 is now energized in a circuit from battery, 37, 31^a, 37^a, 38^a, 27^e, 25^c, 26^b, 23^b, to earth, so that the brushes of the first 105 final selector switch FSI are now moved from position 8 to which they were moved in response to the transmission of the tens digit of the called line. When the eleventh contacts are reached it will be remembered that the circuit of the relay 23 is now opened at the contact *f* of the relay 32 so that the brushes of the first final selector switch FSI are moved past the eleventh set of contacts and the stepping magnet 37 continues to 110 operate to step the brushes of the switch on until the first normal set of contacts with which they are shown in engagement in the drawings, is reached. In this position a circuit is closed for the sensitive relay 23 115

120

125

130

135

from battery, 23, normal contact engaged by brush g^1 of FSI, normal contact and brush g^3 of final selector switch FSII, 28^a, 25^a, 26^a, 27^a, to earth. Relay 23 energizes immediately the first normal contacts are reached and opens at its contact b the circuit before traced for the stepping magnet 37 of the first final selector switch so that the brushes of this switch are brought to rest in their first normal position. The brushes are moved from this position in response to the transmission of the units digit and as the relay 28 is energized the brushes e_1 , f_1 and g_1 will be used in the extension of the call to the called party's line, the other set of brushes of the first final selector switch FSI being disconnected at contacts h , d and f of relay 28. The second final selector switch FSII remains in its normal position throughout the call.

9 dialed as tens digit.

Should the calling subscriber transmit the digit 9 as the tens digit of the called subscriber's number the brushes of the first final selector switch FSI will be moved into engagement with the ninth set of terminals in the bank of the switch and in this position a circuit will be closed for the relay 32 from battery, left-hand winding of 33, 18^a, 25^b, 28^a, f^2 and normal contact engaged thereby, f and contact 9 engaged thereby, left-hand winding of 32, 26^b, to earth. The relay 32 energizes and closes a locking circuit for itself as before explained and opens at its contact f the circuit of the relay 23 so that when the stepping magnet 37 of the first final selector switch FSI rotates the brushes of the switch automatically into engagement with the eleventh set of contacts the circuit of the relay 23 is not closed in this position and the stepping magnet 37 operates to rotate the brushes of the switch back into engagement with their first normal contacts with which they are shown in engagement in the drawings. When this position is reached a circuit is closed for the relay 23 from battery, 23, 34^a, normal contact engaged by brush g , 30^b, normal contact engaged by brush g^2 , 28^a, 25^a, 17, earth. The relay 23 immediately energizes and opens at its contact b the circuit for the stepping magnet 37 of the first final selector switch FSI. The brushes of this switch have thus been restored to normal position, from which position they are moved in response to the transmission of the units impulses, and as the relay 29 was not energized relay 28 remains deenergized and brushes e , f and g are connected to the talking circuit at contacts h , d and f of the relay 28 so that these brushes are used in the extension of the call to the called party's line. The second final selector switch FSII remains inoperative throughout the call while the

brushes e_1 , f_1 and g_1 of the first final selector switch remains disconnected.

2 dialed as the tens digit.

Upon the transmission of 2 as the first digit of the desired party's number the brushes of the first final selector switch FSI will be moved by the operation of the magnet 37 in the manner before described into engagement with the second contacts in the bank, and at the end of this series of impulses upon the deenergization of relay 25 a circuit is closed for the relays 31 and 23 from battery, 23, 32^a, left-hand winding of 31, second contact engaged by brush g of the first final selector switch FSI, 30^a, normal contact engaged by brush g^2 of the second final selector switch FSII, 28^a, 25^a, 17, to earth. A circuit is also closed for the relay 27 from battery, left-hand winding of relay 33, 18^a, 25^b, 28^a, f^2 , normal contact engaged thereby, brush f and second contact engaged thereby, right-hand winding of 27, 26^b, to earth. Relay 27 upon operating closes at its contact a a circuit for the relay 25 from battery, right-hand winding of relay 25, 27^a, to earth. At its contact g relay 27 also closes a circuit for the relay 18 from battery, 18, 20^a, 27^a, 15^a, to earth. As the sensitive relay 23 is energized the circuit for the automatic operation of the stepping magnet 37 for moving the brushes of the first final selector switch FSI automatically from the position to which they are set to the second, or on to the first normal contact is maintained open at contact b of the relay 23 so that the brushes now remain in engagement with the second set of contacts in their bank.

Relay 31 upon energizing closes a locking circuit for itself through its middle and right-hand windings from battery, 34^a, 31, 31^a, to earth and prepares a circuit for the relay 30 by opening a short circuit therearound at its contact f . The relay 31 also disconnects at its contact d the stepping magnet 37 of the first final selector switch FSI and closes at its contact c the circuit of the stepping magnet 38 of the second final selector switch FSII, this circuit now being traceable from battery, 38, 31^a, 24, 17^a, 14^a, 13^a, 23^a, to earth, so that the units impulses of the called party's number will be transmitted to stepping magnet 38 and will operate the second final selector switch FSII instead of the first final selector switch FSI. As the relay 28 is deenergized the brushes e^2 , f^2 and g^2 will be the brushes used in extending the connection to the desired subscriber's line and these brushes will remain in engagement with their first normal contacts, in which position they are shown in the drawings, until moved therefrom in response to the units impulses in the manner hereinafter to be more fully described.

3 dialed as tens digit.

Should the called party's number comprise the digit 3 as the tens digit, the calling subscriber upon operating his dial switch in accordance with this digit will cause the brushes of the first final selector switch FSI to be removed from their normal position into engagement with the third contacts in the bank in the manner before described. In this position a circuit is closed for the middle winding of the relay 31 from battery, 34^c, middle winding of relay 31, 32^b, contact 3 engaged by brush *g* of the first final selector switch FSI, 30^a, normal contact engaged by brush *g*² of the second final selector switch FSII, 28^c, 25^f, 17, earth. Relay 29 is also energized in a circuit from battery, right-hand winding of 29, contact 3 engaged by brush *e* of the first final selector switch FSI, normal contact engaged by brush *e*² of the second final selector switch FSII, 28^b, 25^h, 18^d, right-hand winding of relay 33 to earth. Relay 29 closes a locking circuit for itself at its contact *c* through the slow operating relay 28 from battery, 28, left-hand winding of 29, 29^c, 15^e, to earth. Relay 28 disconnects the brushes *c*², *f*² and *g*² and *e*, *f* and *g* from the talking circuit. A circuit is also closed for the relay 27 from battery, left-hand winding of 33, 18^f, 25^b, 28^c, *f*³ and normal contact engaged thereby, *f*₁ and contact 3 engaged thereby, right-hand winding of relay 27, 26^b to earth. A circuit is also closed for the relay 23 from battery, 23, 32^f, brush *g*¹ and contact 3 engaged thereby, normal contact engaged by brush *g*³, 28^e, 25^f, 17 to earth. Relay 23 operates before relay 27 and opens the stepping circuit for the stepping magnet 37 so that the brushes of the first final selector switch FSI do not move from engagement with the third set of contacts in their bank and as the relay 28 is energized the brushes *e*³, *f*³ and *g*³ of the second final selector switch FSII are connected to the talking circuit so that these brushes are used in the extension of the call.

4 dialed as the tens digit.

Upon the calling subscriber operating his dial switch in accordance with the digit 4 constituting the tens digit of the called number the brushes of the first final selector switch FSI are moved into engagement with the fourth set of contacts in the bank of the switch and in this position a circuit is closed for the relay 31 which may be traced from battery, 34^c, middle winding of relay 31, 32^b, contact 4 engaged by brush *g*, of the switch FSI, 30^b, normal contact engaged by brush *g*² of the second final selector switch FSII, 28^c, 25^f, 17, to earth. Relay 31 energizes and locks by closing its contact *a*. A circuit is also closed for the

relay 27 from battery, left-hand winding of 33, 18^f, 25^b, 28^a, brush *f*² engaging the normal contact of second final selector switch FSII, brush *f* engaging the fourth contact of the first final selector switch FSI, right-hand-winding of relay 27, 26^b, to earth. The relay 27 closes its contact *c* thereby locking itself directly to battery in a circuit from battery, 34^c, resistance 60, 27^e, both windings of relay 27, 26^b, to earth. Relay 27 also closes at its contact *a* a circuit for the relay 25 from battery, right-hand winding of 25, 27^a, to earth. The relay 25 thereupon energizes and opens the connection between the talking circuit and the brushes of the final selector switches. A circuit is also closed for the relay 18 from battery, 18, 20^d, 27^e, 15^c, to earth. The operation of the relay 31 disconnects at its contact *d* the stepping magnet 37 of the first final selector switch FSI from the impulse circuit and substitutes therefor the stepping magnet 38 of the second final selector switch FSII. A circuit is now closed for the stepping magnet 38 from battery, 38, 31^c, 37^a, 38^a, 27^e, 25^o, 26^h, 23^b, to earth. This circuit it will be noted includes the self-interrupting contact *a* of the stepping magnet 38 so that this stepping magnet now operates automatically to step the brushes of the second final selector switch FSII from their normal position in which they are shown in the drawing into engagement with the second normal or eleventh set of contacts in the bank. When this second set of normal contacts is reached a circuit will be traced for the sensitive relay 23 from battery, 23, 32^f, second normal or eleventh contact engaged by brush *g*² of FSII, 28^c, 25^e, 26^f, 27^a, to earth. The relay 23 immediately energizes upon the brush reaching the eleventh terminal and opens at its contact *b* the circuit of the stepping magnet 38 so that the brushes of the final selector switch FSII are brought to rest in engagement with the eleventh set of contacts in the bank and from this set of terminals they are adapted to be moved in accordance with the units impulses in the manner hereinafter described.

5 dialed as tens digit.

Upon the calling subscriber dialing 5 as the tens digit brushes of the first final selector switch FSI are moved 5 steps into engagement with the fifth set of contacts in the bank of the switch and in this position a similar circuit to that before traced, when 4 was dialed as the tens digit, is closed for the relay 31 and this relay energizes, closes a locking circuit for itself, disconnects the stepping magnet 37 of the first final selector switch FSI and substitutes therefor the stepping magnet 38 of the second final selector switch FSII. In addition a circuit is closed for the relay 29 from battery, right-hand

winding of 29, fifth contact engaged by brush e of FSI, normal contact engaged by brush e^2 of FSII, 28^h, 25^h, 18^d, right-hand winding of 33 to earth. Relay 29 upon energizing, closes its contact c and thereby completes a locking circuit for itself through the winding of the slow operating relay 28 from battery 28, left-hand winding of 29, 29^e, 15^e, to earth. The relay 28 thereupon energizes and disconnects at its contacts h , d and f the brushes e^2 , f^2 and g^2 of the second final selector switch FSII and the brushes e , f and g of the first final selector switch FSI and connects up the remaining brushes. A circuit is also closed for the relay 27 which may be traced from battery, left-hand winding of 33, 18^f, 25^b, 28^d, F² and normal contact engaged thereby, f and the fifth contact engaged thereby, right-hand winding of 27, 26^b, to earth. Relay 27 thereupon energizes and closes a locking circuit for itself from battery, 34^e, resistance 60, 27^c, both windings of relay 27, 26^b, to earth. Relay 27 at its contact a closes a circuit for the relay 25 from battery, right-hand winding of relay 25, 27^a, to earth. A circuit is also closed for the relay 18 from battery, 18, 20^d, 27^e, 15^e, earth. A circuit is thus closed for the stepping magnet 38 of the second final selector switch FSII, from battery, 38, 31^e, 37^a, 38^a, 27^e, 25^c, 26^a, 23^b, to earth. This stepping magnet thereupon operates to rotate the brushes of the second final selector switch FSII eleven steps from their first normal position in which they are shown standing in the drawing into engagement with their second normal or eleventh set of contacts in the bank of the switch and in this position a circuit is closed for the relay 23 from battery, 23, 32^f, second normal or eleventh contact engaged by brush g^3 of FSII, 28^e, 25^e, 26^f, 27^a, to earth. Relay 23 energizes immediately the brush g^3 engages the eleventh contact and opens at its contact b the circuit for the stepping magnet 38 so that brushes of the second final selector switch FSII are brought to rest in engagement with the second normal set of contacts in its bank and from this position the brushes are stepped in accordance with the units impulses in the manner hereinafter to be described.

It will thus be seen that in accordance with the first or tens digit of the called party's number the brushes of the first final selector switch FSI are moved by means of the stepping magnet 37 into engagement with a particular set of contacts in the bank of the switch depending upon the number of impulses transmitted for the first digit of the called number. In this position various circuits are closed and relays energized which determine: (1) which switch shall be used in the extension of the connection to the desired line, (2) which set of

brushes of this selected switch shall be operatively connected to the talking circuit and (3) the position from which the brushes of the selected switch shall be moved in response to the transmission of the units impulses. In the following table these operations will be made clear:

Tens digit dialed.	Final selector switch selected.	Brushes selected.	Normal position from which brushes are moved for units impulses.
6	FSI	e, f , and g	11th.
7	FSI	e^1, f^1, g^1	11th.
8	FSI	e^1, f^1, g^1	1st.
9	FSI	e, f, g	1st.
2	FS2	e^2, f^2, g^2	1st.
3	FS2	e^3, f^3, g^3	1st.
4	FS2	e^2, f^2, g^2	11th.
5	FS2	e^3, f^3, g^3	11th.

In the drawing the test contacts of the lines are numbered in accordance with their designation.

Upon the calling subscriber operating his dial switch in accordance with the second or units digit of the called subscriber's number these impulses will be transmitted to either the stepping magnet 37 or the stepping magnet 38 depending upon whether the relay 31 has been energized or not during the operation of the switch FSI for the tens impulses. If the relay 31 is energized stepping magnet 37 is disconnected at its contact d and the stepping magnet 38 substituted therefor at contact c of relay 31. The relay 14 will deenergize a number of times in response to the dialing of the units impulses and will close at its contact d the impulse circuit extending through the particular stepping magnet connected by the relay 31. This may be traced from battery, either through the stepping magnet 37 and contact 31^d or stepping magnet 38 and contact 31^e, 24, 17^a, 14^d, 13^e, 23^a, to earth. The connected stepping magnet thereupon operates to rotate the brushes of either the first or the second final selector switches, from the position in which these brushes stand, in accordance with the units impulses. Upon the first impulse transmitted relay 24 energizes and closes a circuit for the relay 26 from battery, 26, 24^a, to earth. Relay 26 thereupon energizes and closes at its contact e a circuit for the relay 25 from battery, right-hand winding of relay 25, 26^e, to earth. At the end of the units impulses the relay 24 deenergizes and opens the circuit before traced for relay 26 which in turn deenergizes and by closing its make-before-break contact f connects the right-hand winding of the relay 25 to the test brush to be used in extending the call. This circuit may be traced for example from battery, right-hand winding of 25, 26^f, 25^e, 28^f, g^2 , and normal contact engaged thereby, 30^b, brush g , engaging the test terminal of the called line. 130

If this line is found busy, that is, if it is engaged in a call either as a called or as a calling line the test terminal of the called line will be connected either to earth through the low resistance winding of relay 17 of another connector switch or to earth through the low resistance winding of the test relay 16 of another line finder switch. In any event if the line is busy the potential of the test terminal is such as to cause relay 25 to be maintained energized in a circuit from battery, right-hand winding of 25, 26^e, 25^e, 28^f, *g*², normal contact engaged thereby, 30^b, *g*, and test terminal of the called line engaged thereby, low resistance winding of relay 17 or 16 to earth according as the called line is busy as a called line or a calling line, respectively.

As the relays 23 and 27 are deenergized at the end of the units selecting operation, a circuit is closed, upon the deenergization of the relay 26, with the relay 25 energized, for the relay 21 from battery, winding of relay 21, contact 27^f, 25^e, 26^h, 23^b, to earth. The relay 21 thereupon energizes and closes a circuit from battery, both windings of relay 20, 21^e, 22^d, to earth. Relay 20 energizes and opens at its contact *d* the circuit of the relay 18 so that this relay deenergizes. The relay 20 also closes a locking circuit for the relay 25 from battery, both windings of 25, 20^e, 15^e, to earth. At its contact *a* the relay 20 closes a circuit for the relay 50 of the tone circuit and relay 19 of the connecting circuit from battery, 50, right-hand winding of 19, 20^a, 15^e, to earth. The relay 50 initiates the operation of the tone circuit shown at the left-hand lower corner of the drawing and this apparatus thereupon operates in the manner fully before described to generate a tone in the secondary winding of the tone coil 53. The energization of the relay 19 causes the secondary winding of the tone coil to be connected to the talking circuit at contacts *a* and *c* of relay 19 so that the calling subscriber now hears the busy tone and knows that the called line is busy and will thereupon hang up his receiver and release the apparatus in the manner to be hereinafter described. It will be noted that the tone circuit is used for generating both the dialing and busy tones but no confusion will result from this as the busy tone when transmitted occurs after the impulses have been dialed while the dialing tone will reach the calling subscriber soon after he lifts his receiver.

Should the called line be found free, no potential is found upon the test terminal thereof to maintain the relay 25 energized so that this relay deenergizes and a circuit will thereupon be closed for the relay 40 of the ringing circuit apparatus RA shown at the right-hand lower corner of the drawing, from battery, 40, 18^a, 25^d, 26^h, 23^b, to

earth. The relay 40 initiates the operation of the ringing apparatus. This operation being as follows: The closure of contact *c* of relay 40 closes a circuit for the relay 41, from battery, 41, 43^b, 40^e, to earth. Relay 41 thereupon energizes and closes at its contact *a* a circuit for the relay 42 from battery, 42, 41^e, 40^e, to earth. The relay 42 closes at its contact *a* a circuit for the relay 43 from battery, 43, 42^e, 40^e, to earth. Relay 43 upon energizing closes a locking circuit for itself from battery, 43, 43^e, 47^a, 40^e, to earth. The relay 43 also opens at its contact *b* the energizing circuit of the relay 41 so that this relay now deenergizes and opens the circuits of the relay 42 at its contact *c* so that this relay deenergizes and causes the circuit to be closed for the stepping magnet 47 from battery, 47, 43^g, 42^d, 40^e, to earth. The stepping magnet upon energizing opens its contact *a* thereby opening the locking circuit of the relay 43 so that this relay deenergizes and opens at its contact *g* the circuit before traced for the stepping magnet 47 whereby the stepping magnet deenergizes and steps the brush 47^b one step from the position in which it is shown into engagement with the next contact to the right thereof. Upon the relay 43 deenergizing, the circuit of the relay 41 is again closed and this relay causes the relays 42 and 43 to energize as before described and close the circuit of the stepping magnet 47. The relays 41, 42 and 43 are constructed so as to attract their armature slowly and in this manner by properly adjusting the time of operation of the relays the stepping magnet 47 may be caused to step its brush 47^b one step from one contact to another in its bank at definite intervals of time.

The relay 40 upon energizing also closes a circuit for the relay 44 from battery, 44, one of the contacts connected thereto engaged by the brush 47^b, 40^e, to earth. The relay 44, upon energizing closes at its contact *a* a circuit for the relay 45 from battery, 45, 46^b, 44^a, to earth. Relay 45, upon energizing, closes at its contact *a* a circuit for the relay 46 from battery, 46, 45^a, 44^a, to earth. The relay 46 upon energizing opens at its contact *d* the circuit of the relay 45 so that this relay thereupon deenergizes and opens at its contact *a* the circuit of the relay 46. This relay in turn deenergizes and again connects the relay 45 to the contact of the relay 44. Relays 44, 45 and 46 are arranged to operate slowly so that the contact *a* of the relay 45 is opened and closed at definite intervals of time. Upon the deenergization of the relay 45 it closes at its contact *b* a circuit through the relay 46 from battery, primary winding of the ringing transformer 48, 45^d, 44^a, to earth so that current flows through this primary

winding. When this circuit is broken upon the energization of the relay 45 current flowing through the primary winding of the transformer 48 is interrupted and current is thereby induced in the secondary winding of the ringing transformer. This operation is repeated as long as the relay 44 is energized, that is, as long as the brush 47^b of the stepping magnet 47 engages a contact connected to this relay. As shown in the drawings the first four contacts are connected to the relay and the brush 47^b is then moved over its entire set of contacts until it returns to normal before the relay 44 is again energized. In the actual switch the last contact in the row of contacts shown as being connected to the relay 44, is preferably adjacent the first contact upon which the brush is shown testing in the drawings, that is, the contacts are arranged in a circle. Further, the brush 47^b is of such a width that it engages the next successive contact during its movement over the bank of contacts, before leaving the first contact, that is, the circuit of the relay 44 is not broken during the time the brush 47^b passes over from one contact to another of the contacts connected to the relay. In this manner an alternating electromotive force is generated in the secondary winding of the ringing current transformer 48, the frequency of the alternations depending upon the rapidity of the operation of the relay 45 while the interval between successive currents depends upon the speed of operation of the brush 47^b.

It will be remembered that upon the called line being found free the relay 25 deenergizes and the current generated in the secondary winding of the transformer 48 thereupon flows to the called line. The path of the ringing current may be traced from battery, left-hand winding of relay 20, 18^a, 25^b, 28^a, brush f^2 (assuming that this brush is used in the extension of a call) thence through the called line and back to brush e^2 , 28^b, 25^b, 18^a, 27^m, secondary winding of the ringing transformer 48 to earth. This current passes through the bell at the called substation and actuates the same to attract the attention of the subscriber thereat and this subscriber upon lifting his receiver and completing a metallic loop through the substation causes direct current to be superimposed upon the alternating current from battery connected to the left-hand winding of relay 20. The superimposition of this direct current will cause the relay 20 to energize, this relay having remained inert during the transmission of alternating current therethrough. The relay 20 upon energizing, opens at its contact d the circuit of the relay 18 so that this relay deenergizes and opens at its contacts c and e the circuit before traced for the ringing current so that ringing is stopped immedi-

ately upon the response of the wanted party whether he lifts his receiver during a silent or during a ringing period. By opening its contact e the relay 18 opens the circuit of the relay 20 so that this relay deenergizes and the slow operating relay 19 is prevented from energizing.

Connection has thus been extended to the called line and conversation may take place between the calling and called parties. Current is supplied to the calling party through windings of the relay 14 while the called party is supplied through windings of the relay 33.

Release of connection.

At the end of the conversation the release of the apparatus takes place under the control of the calling party in the following manner. Upon the calling party restoring his receiver to the switch-hook the relay 14 deenergizes and opens the circuit of the relay 15 so that this relay deenergizes after a short interval of time. Relay 15, by closing its contact d short circuits the relay 17 through contact g of the relay 34 so that the relay 17 now deenergizes and opens the circuit of the test relay 16 at its contact e . Relay 16 deenergizes and at its contact b short circuits the relay 13 so that this relay thereupon deenergizes and opens the connection to the calling line so that the calling line will now test free. Relay 13, upon deenergizing, closes a circuit for the relay 32 from battery, 34^c, 13^a, 31^f, left-hand winding of relay 32, 26^b, to earth. Should the relay 31 have been energized during the establishment of the connection the relay 30 is included in the circuit just traced as the short circuit therearound is opened at contact 31^f and this relay will also energize therein. Relay 32 upon energizing closes a circuit for the relay 27 from battery, 34^c, resistance 60, 32^a, both windings of relay 27, 26^a, to earth. Relay 27 energizes and closes at its contact a a circuit for the relay 25 from battery, right-hand winding of relay 25, 27^a to earth.

Should the relay 31 have been energized during the call which indicates that the final selector switch FSII has been used in extending the connection, it is necessary first to restore this switch to normal and then the final selector switch FSI from the position in which the latter switch has been set in response to the dialing of the tens digit. The energization of the relay 27 causes a circuit to be closed during the energization of the relay 31 for the stepping magnet 38 of the second final selector switch FSII from battery, 38, 31^b, 37^a, 38^a, 27^b, 25^c, 26^b, 23^b, to earth. The stepping magnet 38 thereupon operates automatically opening its own energizing circuit at each energization at its contact a to rotate the brushes

- ⁵ e^2, f^2, g^2, e^3, f^3 and g^3 , of the final selector switch FSII from the position in which they are set after the dialing of the units impulses back to their first normal position in which they are shown standing in the drawing. When the first normal position is reached a circuit is closed for the relay 23 from battery, 23, 30^a, normal contact engaged by brush g^2 of the final selector switch FSII
- ¹⁰ 28^t, 25^t, 26^t, 27^a, to earth. The relay 23 immediately energizes upon the brush g^2 closing this circuit and opens at its contact b the circuit before traced for the stepping magnet 38 so that the second final selector switch is brought to rest with its brushes in engagement with the first normal set of contacts.
- Upon the relay 23 closing its contact a the right-hand windings of the relay 31, that is, the locking circuit of this relay are short-circuited, the earth connection being from earth, 23^a, 13^t, 30^c, to the middle and right-hand windings of relay 31, the other side of these windings being connected to earth through contact a of the relay 31. The relay 31 thereupon deenergizes and at its contact c it opens the circuit of the stepping magnet 38 and at its contact d substitutes therefor the stepping magnet 37. The relay 31 by closing its contact f short circuits the relay 30 and this relay thereupon deenergizes. The relay 30 upon closing its contact b connects the normal contact engaged by brush g^2 of the second final selector switch FSII to the brush g of the final selector switch FSI. The circuit of the relay 23 is also opened at the contact a of the relay 30 so that this relay thereupon deenergizes.
- ⁴⁰ Under these conditions, a circuit is closed for the stepping magnet 37 of the first final selector switch FSI from battery, 37, 31^a, 37^a, 38^a, 27^t, 25^c, 26^t, 23^b, to earth. The stepping magnet 37 thereupon operates automatically opening its own energizing circuit at each energization at its contact a to step the brushes, e, f, g, e_1, f_1, g_1 , of the first final selector switch FSI from the position in which these brushes are resting back to their first normal position in which they are shown in the drawings and when this position is reached a circuit is closed for the relay 23 from battery, 23, 34^c, normal contact engaged by brush g , 30^b, normal contact engaged by brush g^2 , 28^t, 25^c, 26^t, 27^a to earth, so that the relay 23 immediately energizes and opens at its contact b the circuit before traced for the stepping magnet 37 so that the brushes are brought to rest in engagement with their first normal set of contacts. Relay 23, upon energizing, now closes a circuit at its contact a for short-circuiting the winding of the relay 34 one side of the relay 34 being connected to earth from earth, 23^a, 13^t, 30^d, to the wind-

ing of relay 34, the other side of relay 34 being connected to earth through the winding of the relay 17. The relay 34 thereupon deenergizes and opens at its contact c the circuit of the relay 32 and this relay, upon deenergizing, opens the circuit before traced for the relay 27 at its contact c so that the apparatus is now completely restored to its normal position.

Operation of final selector switch as rotary connector.

It may be desirable to arrange that the final selector switch which establishes the connection to the desired line operates as a rotary connector switch over certain groups of contacts, the contacts of this group being the terminals of lines located, for example, in the same room or office and which lines would be numbered successively. Such an arrangement permits the final selector switch, upon engaging the first or subsequent terminal of the group except the last, and finding the same busy, to rotate automatically until an idle line in the group is found so that the connection is extended to one of these lines without delay. It is of course arranged that in any case, if the last line in the group is free or busy, the final selector switch will be brought to rest with its brushes in engagement with the terminals thereof.

To carry this out it is necessary to provide the slow acting relay 21 and marginal relay 22. The lines of the group over which the final selector switch is desired to hunt, with the exception of the last line in the group, will be provided with suitable individual resistances as 2, connected between the cut-off relay of the line and the test terminal of the line in each of the connecting switches, and 3 between the cut-off and the test terminal of the line in the line finder switch. Such a line is shown at T₂, Fig. 3. The operation of this arrangement will be as follows, it being assumed firstly that the final selector switch FSI has extended connection to an ordinary line, that is, a line which is not one of the group over which this switch hunts, and has found this line busy. The relay 25 will be maintained energized over the test brush of the switch in the manner hereinbefore described and a circuit is thereupon closed for the slow operating relay 21 from battery, 21, 27^t, 25^c, 26^t, 23^b, to earth. The relay 21 closes at its contact a a circuit for the relay 22 and at its contact c a circuit for the relay 20. As, however, the line to which the connection has been extended is assumed to be an ordinary line, the test relay 22 which is marginal does not receive sufficient current to cause it to energize, it being shunted by the connection to earth through the low resistance winding of the test relay 16 of

the line finder switch should the desired line be busy in another connection as a calling line or through the low resistance winding of the relay 17 of the connector switch should the desired line be engaged as a called line. The relay 22, therefore, although its circuit is closed at the contact *a* of relay 21, does not open its contact *d* so that a circuit is now closed from battery, 10 both windings of relay 20, contact 21^a, 22^a, to earth. The relay 20, upon energizing, closes at its contact *e* a locking circuit for the relay 25 in the manner before described and also at its contact *a* a circuit for the 15 relay 19 so that the busy tone is now transmitted to the called subscriber's line by the connection of the secondary winding of the tone coil 53 to the calling line at contacts *a* and *c* of the relay 19.

20 If, however, the line to which the connection has been extended and found busy is a non-final line of the group of lines over which the final selector switch hunts, the connection of the resistance between the 25 cut-off relay and the test contact in the final selector switch or the line finder, causes the potential upon the test terminal to be sufficient to cause the relay 22 to energize in a circuit which may be traced 30 from the test terminal and test brush such as *g* of the first final selector switch FSI, 30^b, first normal contact and brush *g*² of the second final selector switch FSII, 28^c, 21^c, 22, 20^c, 15^c, to earth. The relay 22, upon 35 closing its contact *c*, closes an energizing circuit for the stepping magnet 37 in series with the relay 24 and opens at its contact *d* the circuit for the relay 20. The relay 20 is arranged to attract its armature slowly 40 so that the relay 22 opens its contact *d* before the relay 20 has time to energize. The circuit of the stepping magnet 37 may now be traced from battery, 37, 31^a, 24, 22^a, to earth. The relay 24 energizes in this 45 circuit and at its contact *a* closes a circuit of the relay 26 from battery, 26, 24^a, to earth. The relay 26, upon energizing, opens at its contact *h* the circuit before traced for the relay 21 so that this relay deenergizes 50 and opens at its contact *a* the circuit of the relay 22. Relay 22 by opening its contact *c*, disconnects the stepping magnet 37 so that this stepping magnet now deenergizes 55 and moves the brushes of the first final selector switch FSI one step from the position to which they are set at the end of the units impulses into engagement with the next set of terminals in the group of terminals over which the final selector switch hunts, that is, into engagement with the terminals of the next line.

60 When the relay 22 deenergizes and opens at its contact *c* the circuit of the stepping magnet 37 the relay 24 deenergizes. This relay thereupon opens the circuit of the

relay 26 at its contact *a* and relay 26 upon deenergizing closes its contact *h* and again completes the circuit of the relay 21. The relay 21 closes its contact *a* and again connects the relay 22 to the test brush *g*². If 70 now this second line, into engagement with the terminals of which the brushes of the final selector switch have been moved by the operation of the stepping magnet 37 as described, should be idle, the relay 25 will deenergize and open at its contact *c* the circuit of the relay 21 so that this relay remains deenergized and maintains the circuit of the relay 22 open at contact *e*. It will be remembered that the relay 18 was 80 energized at contact *g* of relay 27 upon the latter energizing and relay 18 then locked up over a circuit from battery, 18, 20^a, 18^c, 15^c, to earth. Upon the deenergization of relay 25 therefore a circuit is closed from battery, 85 40, of the ringing apparatus, 18^a, 25^a, 26^a, 23^b, earth. The relay 40 initiates the operation of the ringing apparatus and ringing current is transmitted to the line from battery, 20, 18^a, 25^a, 28^a, *f*², and normal contact engaged thereby, *f* if FSI is used to extend the call, through the bell at the substation, *c*, *c*², 28^a, 25^b, 18^a, 27^m, through the secondary winding of the ringing transformer 45 90 95 100 105 110 115 120 125 130 135 140 and each final selector switch is provided with two sets of brushes, a connection being extended over a particular set of brushes of a particular final selector switch depending upon the first digit of the called number dialed. It will be readily understood that this principal may be extended in any desired manner and if desired the connecting circuit may terminate in any number of final selector switches connected in parallel and these final selector switches may be provided with any desired number of sets of brushes. With such an arrangement the particular set of brushes and particular final selector switch FS to be used in extending the call would be connected up by the energization of controlling relays, the circuits of which are closed at one of the final selector switches which is operated in response to the impulses representing the first digit of the called subscriber's number. Should, however, it be desired to provide a system for dealing with a smaller number of lines, the connecting circuit may terminate in a single selector switch such as FSI which may be provided with any desired number of sets of brushes and the particular set of brushes to be used would be connected up by means of relays which would be energized over certain brushes of this switch when operated for the first digit of the called subscriber's number. Such an arrangement would necessitate suppression of the relays 28 to 31, inclusive, from the system illustrated in the drawing, together with the final selector switch FSII and its associated stepping magnet 38. closed from battery, left-hand winding of relay 33, 18^f, 25^b, 28^a, f² and normal contact engaged thereby, brush f and tenth contact O engaged thereby, brush d of line finder switch LF and test contact of the calling line engaged thereby, thence through a calling lamp associated with the jack, of the calling subscriber's line upon the attendant's board to earth. The relay 33 energizes and locks itself from battery, 33^c, contact O, brush e, normal contact and brush e², 28^h, 25^h, 18^d, 33, earth. The attendant upon observing the glowing of the lamp plugs into the jack, throws her listening key and communicates with the calling subscriber. The calling subscriber will give the attendant the number she desires in the main exchange and the attendant will plug into a trunk jack of a trunk leading to the main exchange and communicate with the attendant thereat or establish the connection herself by the operation of her dial switch connected to the trunk through the usual trunk dialing key. For calls from the main exchange ringing current projected over the trunk line may be arranged to operate a ringing current relay which would cause a lamp associated with the trunk jack to be lit at the attendant's board. The attendant would then plug into this jack, ascertain the number of the desired line and establish connection by plugging into the jack of the desired line located upon her board. It may further be desired to permit certain subscribers of the private branch exchange to extend connections to the main exchange, all of which may be done by the use of the apparatus illustrated in the drawing.

Calls to the exchange.

40 It may be desired to give facilities to cer-
tain of the subscribers to the system for ex-
tending connections to a main exchange
either automatically or under the control of
an attendant. For this purpose an attend-
45 ant's board would be provided and all sub-
scribers' lines which are to be given facili-
ties for making such calls under the control
of the attendant would terminate upon said
50 board in a jack in addition to terminating
in the terminals of line finder switches and
final selector switches while lines which may
establish connections automatically termi-
nate at the attendant's position in terminals
55 of trunking line finder switches in the man-
ner to be hereinafter described. To extend
a connection to the exchange a subscriber of
the first category would remove his receiver
whereupon a line finder, such as the line
60 finder LF would hunt for the calling line
and would associate a connecting circuit
therewith. A calling subscriber would
thereupon dial the digit 0 and would move
the brushes of the first final selector switch
65 FSI ten steps into engagement with the
contacts O. In this position a circuit is
70 in the banks of trunking line finder
switches at the attendant's position, similar
to the line finder LF in addition to a jack
thereat. The right-hand back contact b of
75 the relay 33 is in this case connected to the
contact O engaged by the brush g of the
final selector switch FSI, the test terminal
d in the bank of the line finder LF remain-
80 ing disconnected so that the relay 33 re-
mains deenergized. The subscriber at the
private branch exchange, upon dialing the
digit 0 to obtain a connection to the main
exchange causes the brushes of the first
85 final selector switch FSI to be moved ten
steps into engagement with the tenth set
of contacts in the bank of the switch and a
circuit is closed for a starting relay 80 at
the attendant's board which, upon energiz-
90 ing, is adapted to close the starting circuits
of the trunking line finder switches, to cause
these switches to hunt to connect an idle
outgoing trunk line to the calling sub-
scriber's line. This circuit may be traced
95 from battery, through the starting relay 80
at the attendant's position, 33^b, contact O
engaged by brush g of first final selector

switch FSI, 30^b, normal contact engaged by brush g^2 of FSII, 28^t, 25^t, 17, earth. The trunking line finder switches are started by the relay 80 and operate in search of the calling line in a manner similar to switch LF, and upon one of these finding the line, an idle trunk line is connected thereto. The calling subscriber may then dial the called number and establish connection with the desired party in the main exchange in the well known manner.

Incoming calls from the main exchange will be established manually by the attendant by plugging into the jack of the desired line.

What is claimed is:

1. In a telephone exchange system, a group of switches at the same switching stage, means to place a particular one of said switches, in one of a plurality of predetermined positions, means operated in accordance with the position taken by said switch to render any one of the group of switches operative, and means to operate said operative switch in the desired manner.

2. In a telephone exchange system, calling lines, a pair of switches at the same switching stage, means for extending any one of said calling lines to said switches, means under the control of the calling line to give one of said switches a preliminary setting, and means operated in accordance with such setting to bring either the same switch or the other switch of the pair under the control of said calling line to extend the connection in the desired manner.

3. In a telephone exchange system, calling lines, called lines, a plurality of switches each capable of completing connections to called lines, means for connecting any one of said calling lines with said switches, means to place one of said switches in one of a plurality of predetermined positions, means to render a particular one of said switches operative in accordance with the position taken by said first switch, and means to operate said operative switch to complete the connection to the called line.

4. In a telephone exchange system, calling lines, called lines, a plurality of switches each capable of completing connections to called lines and each provided with a plurality of brush sets, means for connecting any one of said calling lines with said switches, means to place one of said switches in one of a plurality of predetermined positions, means to render a particular one of said switches operative in accordance with the position taken by said first switch, means also operated in accordance with the position taken by said first switch to determine which of the brush sets of the selected switch shall be effective, and means to operate said switch to complete the connection to the called line through said brush set.

5. In a telephone exchange system, calling lines, called lines, a plurality of switches each capable of completing connections to called lines and each having a plurality of normal positions, means for connecting any one of said calling lines with said switches, means to place one of said switches in any one of a plurality of predetermined positions, means operated in accordance with the positions taken by said switch to render a particular one of said switches operative, means also operated in accordance with the position taken by said first switch to position said operative switch in a particular normal position, and means to advance said operative switch from said normal position to complete the connection to the called line.

6. In a telephone exchange system, calling lines, called lines, a plurality of switches each capable of completing connections to called lines, each provided with a plurality of brush sets and each having a plurality of normal positions, means for connecting any one of said calling lines with said switches, means to place one of said switches in any one of a plurality of predetermined positions, means operated in accordance with the position taken by said switch to select one of said switches, means also operated in accordance with the position taken by said first switch to position the selected switch in a particular normal position, means to advance said switch from said normal position to select the called line, and further means operated in accordance with the position taken by said first switch to determine which brush set of the selected switch shall be effective to complete the connection to the called line.

7. In a telephone exchange system, a plurality of switches each capable of completing connections, each having a plurality of normal positions and each provided with a plurality of brush sets, means to give one of said switches a preliminary setting in which position means are operated for selecting a particular switch, a particular brush set and a particular normal position, and means for moving the selected brush set of the selected switch from the selected normal position to complete the connection.

8. In a telephone exchange system, a calling line provided with an impulse transmitter, a called line, a plurality of switches each capable of completing connections to called lines, each provided with a plurality of brush sets and each having a plurality of normal positions, means to extend said calling line to said selector, means responsive to an operation of said impulse transmitter to give one of said switches a preliminary setting, means operated in accordance with the set position of said switch

to select a particular one of said switches, a particular brush set, and a particular normal position, and means responsive to a subsequent operation of said impulse transmitter to move the selected brush set of the selected switch from the selected normal position to connect with said called line.

9. In a telephone exchange system, calling lines, called lines, a pair of switches each capable of completing connections, means for extending a connection from a calling line to said switches, means under the control of the calling line for placing one of said switches in any one of a plurality of predetermined positions, means responsive to the placing of said switch in certain positions to render said switch operative to complete the connection to the called line, means responsive to placing said switch in other positions to render the second switch of the pair operative to complete said connection, and means under the control of the calling line for completing the connection by means of the operative switch.

25 10. In a telephone exchange system, calling lines, called lines, a pair of switches each capable of completing connections and each provided with a pair of brush sets, means for extending a connection from a calling line to said switches, means under the control of the calling line for placing one of said switches in any one of a plurality of predetermined positions, means controlled in accordance with the position taken by said switch for rendering one of the brush sets of each switch effective, other means for rendering one of said switches effective, and means under the control of the calling line for completing the connection through the brush set of the switch thus rendered effective.

40 11. In a telephone exchange system, calling lines, called lines, a pair of switches each capable of completing connections and each having two normal positions, means for extending a calling line to said switches means under the control of the calling line for advancing one of said switches to any one of a plurality of predetermined positions to determine which switch shall be effective and from which normal position it shall be operated, means for positioning the predetermined switch in said normal position, and means under the control of the calling line for completing the connection.

55 12. In a telephone exchange system, call-

ing lines, called lines, a pair of switches each capable of completing connections, each switch having two sets of brushes and two normal positions, means for extending a calling line to said switches, means to give one of said switches a preliminary setting, means operated in the set position of said switch to determine the normal position from which subsequent selections shall be made, means also operated in the set position of said switch to determine which switch shall be used in such subsequent selections, means for placing said switch in said normal position, and means for operating said switch from said normal position to complete the connection to the called line.

13. In a telephone exchange system, calling lines, called lines, a pair of switches each capable of completing connections, means for extending one of said calling lines to said switches, means to give one of said switches a preliminary setting, means controlled in accordance with said setting for either rendering the said switch operative or for holding said switch in its set position to render the second switch operative, and means under the control of the calling line to cause the operative switch to complete the connection.

5 14. In a telephone exchange system, calling lines, a pair of switches each capable of completing connections, each provided with a pair of brush sets and each having a pair of normal positions, called lines arranged in groups such that each group is characterised by the switch, brush set and normal position used in completing connections thereto, means for extending a calling line to said pair of switches, means under the control of said calling line for placing one of said switches in any one of a plurality of predetermined positions, means operative in accordance with such set position to select the group in which the called line appears, means to position the particular brush set of the particular switch in the particular normal position characteristic of the selected group of called lines, and means under the control of the calling line for operating said particular switch to complete the connection to the called line.

In witness whereof, I hereunto subscribe my name this 12th day of December A. D., 1922.

LIPA POLINKOWSKY.
